UNITED STATES PATENT OFFICE.

EVERETT S. TABER, OF CANTON, MASSACHUSETTS, ASSIGNOR TO SAMSON ELECTRIC COMPANY, OF CANTON, MASSACHUSETTS, A CORPORATION OF MASSACHUSETTS.

ELECTRIC ALARM.

1,254,864.

Specification of Letters Patent. Patented Jan. 29, 1918.

Application filed March 30, 1915. Serial No. 17,987.

To all whom it may concern:

Be it known that I, EVERETT S. TABER, a citizen of the United States, and resident of Canton, in the county of Norfolk and 5 State of Massachusetts, have invented certain new and useful Improvements in Electric Alarms, of which the following is a specification.

This invention relates to an audible signal for fire-alarm and other purposes, and comprising a bell or gong, a hammer, and electro-mechanical means for causing the hammer to strike the bell.

The invention has for its object first to 15 provide improved electro-mechanical hammer-operating means of simple construction, providing for an effective hammer blow by the attraction of an armature to the poles of an electro-magnet, and for a quick 20 partial rebound of the hammer either by the action of a spring or by gravity, and the maintenance of the hammer out of contact with the bell after the blow. The invention also has for its object to provide improved means for protecting the bell, the 25 hammer and the hammer-operating mechanism against injury by water, dust and insects.

To these and other related ends the invention consists in the improvements which I will now proceed to describe and claim.

Of the accompanying drawings forming a part of this specification:

Figure 1 represents a front elevation of 30 a supporting base and a cover, inclosing the bell, the hammer and the hammer-operating mechanism hereinafter described;

Fig. 2 represents a front elevation of the base, the hammer, and the hammer-operating mechanism, the cover and bell being removed;

Fig. 3 represents an edge view of the base, the bell, the hammer, and the hammer-operating mechanism, the hammer being re- 45 tracted and the cover being shown in section;

Fig. 4 represents a section on line 4—4 of Fig. 1, showing the hammer being re- 50 tracted;

Fig. 5 represents a view similar to Fig. 4, the hammer being projected;

Fig. 6 represents a view showing the base and cover in section and an edge view of the bell and the hammer-operating mechanism,

the hammer being mainly concealed by the 55 operating mechanism;

Fig. 7 represents a fragmentary perspective view, showing portions of the hammer and the operating mechanism;

Fig. 8 represents a fragmentary perspective view, showing a portion of the hammer detached;

Figs. 9, 10 and 11 represent fragmentary views, partly in section and partly in elevation, showing different relative positions of 65 the armature and the hammer;

Fig. 12 represents a fragmentary sectional view, illustrating a modification;

Fig. 13 represents a sectional view of the 70 cover detached; and

Fig. 14 represents a fragmentary sectional view, showing a cover composed of sections, one overlapping the other.

The same reference characters indicate the same or similar parts in all the views. 75

In the drawings, 12 represents a base having means, such as ears 13, whereby it may be attached to a support. To the base is attached an electro-magnet, of which 14, 14, are the helically wound spools and 15, 15, 80 the poles. The base is provided with ears or standards 16 supporting pivot screws 17 in alignment with each other. 18 represents an armature located between the standards 16 and mounted to oscillate on the pointed 85 inner ends of the pivot screws 17 from the retracted position shown by Figs. 2, 3, 4, 7 and 9 to the projected position shown by Figs. 5, 10 and 11, the armature being in the last named position when attracted and held 90 by the poles of the electro-magnet. As here shown, the poles 15 are extended outwardly from the spools and enter orifices 19 (Figs. 6 and 7) formed for their reception in the armature.

20 represents the head and 21 the shank of a hammer which is fulcrumed to oscillate on an axis preferably formed by unthreaded portions of the pivot screws 17, the shank 21 being provided with oppositely 100 projecting angular fulcrum-arms 22 (Figs. 7 and 8) having offset ends provided with sockets 23 (Fig. 3) through which said pivot screws pass. The arms 22 extend along one edge of the armature, and its socketed ends 105 project over opposite ends of the armature, as shown by Fig. 7.

The hammer shank is provided with a le-

ver arm 25 which projects over the inner side of the armature 18, and is so formed and arranged that when the armature is attracted by the magnet it imparts movement to the 5 arm and to the hammer, swinging the hammer head toward the bell 26, which is supported in suitable relation to the hammer, preferably by a bracket 27 attached to the base. The lever arm 25 is held in yielding 10 contact with the armature either by a spring 28 or by gravity, as hereinafter described.

The relative arrangement of the armature, the bell, the lever arm 25, and the hammer is such that when the armature is in its attracted 15 position and the lever arm is in contact with the armature, the hammer head is slightly separated or retracted from the bell as shown by Fig. 11. The lever-arm 25 has a greater amplitude of movement than 20 the armature so that when the armature moves from the position shown by Fig. 9 to that shown by Fig. 10, the movement imparted by it to the arm 25 and to the hammer is continued by the momentum of the 25 hammer, until the hammer head strikes the bell, the arm 25 being at this moment separated from the armature, as shown by Fig. 10. The hammer is therefore free to rebound to the position shown by Fig. 11 and 30 separate its head from the bell, so that the vibrations of the bell are not muffled by the hammer.

In the embodiment of the invention shown by Figs. 1 to 11 inclusive a spring 28 is provided to hold the lever arm 25 yieldingly against the armature. Said spring is interposed between the outer side of the armature and an abutment arm 30 formed on the hammer shank and projecting over the outer 40 side of the armature, the spring being preferably attached to the armature. The spring is preferred when the base is in a vertical plane, and the hammer shank is approximately vertical, but when the base and 45 hammer shank are arranged horizontally, the spring and the abutment arm 30 may be omitted, as shown by Fig. 12, the lever arm 25 being held against the armature by the weight of the hammer.

50 It will be seen that the aligned pivot screws 17 constitute an axis that is common to the armature and the hammer, and that there is no rubbing or sliding contact between the lever arm 25 and the armature to 55 cause frictional resistance to the movement of the hammer by the armature, hence the force of the armature, when it is attracted, is fully utilized to impart a forcible striking movement to the hammer.

60 The center of the bell is preferably opposite the central portion of the electro-magnet, as shown, so that the bell, the hammer and the hammer-operating mechanism constitute a compact group adapted to be protected 65 by a dome-shaped cover 32. Said

cover has ears 33 which are screwed or bolted to the base. The crown of the cover is provided with sound-conducting openings 34 preferably arranged radially, as shown by Figs. 1 and 13. To prevent the admission of dust and insects the said openings are screened with wire cloth 35, or other foraminous material, preferably formed in a single concavo-convex sheet fitting the interior of the cover and extending across the openings. 70 The cover may be provided with beads or flanges 36 surrounding said openings and projecting outwardly from the outer surface of the cover to prevent water from rain and snow, and trickling from the upper surface of the cover, from entering the openings. The screening material may be of sufficiently fine mesh to prevent any objectionable entrance of rain or snow into the casing. 75

The cover may be composed of sections 32^a and 32^b, as shown by Fig. 14, the lower edge of the upper section overlapping the upper edge of the lower section to shed water flowing downwardly from the upper 80 surface of the cover. The openings 34 may be formed only in the lower section, the upper section constituting an overhanging closed roof. 85

Having described my invention, I claim: 95

1. An electric alarm comprising a bell, an electro-magnet, an oscillatory armature for said magnet, and an oscillatory bell hammer substantially coaxial with said armature and provided with a lever arm which 100 is permanently out of circuit and movable by the armature when the latter is attracted, said arm being normally held in yielding contact with the armature and separable therefrom by the momentum of the hammer, so that the arm has oscillatory movements of greater amplitude than those of the armature, whereby, when the armature is attracted, the hammer is first projected 105 against the bell and is then slightly retracted therefrom. 110

2. An electric alarm comprising a bell, an electro-magnet, an armature for said magnet, a bell hammer, means oscillatively supporting said armature and hammer with 115 their axes of oscillation substantially in alignment, and an arm on the hammer arranged to be moved forward by the armature when the latter is attracted, said arm being permanently out of circuit, means being provided for yieldingly holding the said arm against the armature and permitting an additional forward movement of the arm by the momentum of the hammer after the forward movement of the armature is arrested, said additional movement projecting the hammer against the bell and being followed by a slight retracting movement. 120

3. An electric alarm comprising a bell, an electro-magnet, an armature for said 125

5 magnet, fixed alined pivots oscillatively supporting said armature, and a bell hammer having laterally projecting fulcrum arms mounted to turn on said pivots and a lever arm arranged to bear on one side of the armature and movable thereby when the armature is attracted, said lever arm being normally held in yielding contact with the armature and being separable therefrom by the momentum of the hammer to permit a greater amplitude of movement of the arm than of the armature.

10 4. An electric alarm comprising a bell, an electro-magnet, an armature for said magnet, fixed alined pivots oscillatively supporting said armature, and a bell hammer having laterally projecting fulcrum arms mounted to turn on said pivots and a lever arm arranged to bear on one side of the armature and movable thereby when the armature is attracted, the hammer being also provided with a spring abutment projecting over the opposite side of the armature, and a spring interposed between said armature and abutment and normally holding the said lever arm in yielding contact with the armature.

15 5. An electric alarm comprising a bell, a base having spaced-apart standards, an electro-magnet having its poles adjacent to said standards, pivots supported by said standards and engaged with the armature, and a hammer having oppositely projecting angular fulcrum arms projecting over the ends of the armature and mounted to turn

20 on said pivots, and a lever arm projecting over the inner side of the armature, normally held in yielding contact therewith, and separable therefrom by the momentum of the hammer.

25 6. An electric alarm comprising a bell, a base having spaced-apart standards, an electro-magnet having its poles adjacent to said standards, pivots supported by said standards and engaged with the armature, a hammer having oppositely projecting angular fulcrum arms projecting over the ends of the armature and mounted to turn on said pivots, a lever arm projecting over the inner side of the armature, and a spring abutment projecting over the outer side of the armature, and a spring interposed between said armature and abutment and normally holding the said lever arm in yielding contact with the armature.

30 7. An electric alarm comprising a base having an outwardly projecting bracket, a bell supported by said bracket, an oscillatory hammer fulcrumed between the base and the bell, electro-mechanical hammer-operating mechanism located between the base and the bell, and a protective cover attached to the base and inclosing the bell, the hammer, and the hammer-operating mechanism, said cover having sound conducting openings, and outwardly projecting flanges surrounding said openings.

In testimony whereof I have affixed my signature.

EVERETT S. TABER.
